PASTE SUPPLIER

Karl Erik Granstedt, Stockholm, Sweden, assignor to Aktiebolaget Formator, Stockholm, Sweden, a Swedish joint stock company

Application November 7, 1932, Serial No. 641,654
In Sweden October 10, 1932.

29 Claims. (Cl. 131—42)

This invention relates to an apparatus for supplying paste, preferably to thin objects resting on a curved plate or the like. Such a plate is the rolling table in cigar machines, of the known kind called bunchers. In machines of the last mentioned kind a tobacco filler is wound in a tobacco leaf, which is applied to an apron, resting on the rolling table. Before being wound the edge of the leaf (possibly part of the edge) which is wound around the filler, is supplied with paste in order to ensure the sealing of the tobacco leaf. The leaf may have varying shapes or sizes, depending upon the shape and size of the finished product. As for the winding generally only one half of the leaf (which has been divided along its stem) is used, it is customary that either so called right hand leaves or left hand leaves are used. The leaf is usually applied to the apron in such a way that the edge to be supplied with paste has an oblique position relative to the direction of the winding, and because as per above two kinds of leaves (different halves) are used, the oblique positions of these edges become opposite to each other. Because the rolling table for constructive reasons should have a curved shape, the leaf edge when it is lying obliquely will form a curved line of rather irregular shape. The shape of this curved line varies as soon as the front edge of the leaf varies to its position either by swinging (angular adjustment) or by parallel movement.

The present invention relates to a paste supplying device developed so that it can be adjusted conveniently to be used for any position or direction of the part of the leaf (the leaf edge) which is to be supplied with paste, and further the quantity of the paste supplied along the whole leaf or at parts of same can be conveniently accommodated to various purposes. This latter is especially desirable, because thereby the pasting device becomes useful for any kind of bunch and if the bunch is to be subsequently divided. According to the invention the paste supplying apparatus, comprising a container equipped with valves, the container being moved against a surface or the like, which opens the valves, is mainly characterized in that the stop (shoulder) of each valve is adjustable relative to the stops of the other valves.

On account of the adjustability of the valves relative to each other the container may conveniently be developed slidably and rotatably adjustable.

A preferred embodiment of the device according to the invention is fully described in the

specification and illustrated in the accompanying drawings, said embodiment being specially adapted for a cigar-machine and the paste supplying device being adapted to move vertically when operating.

Fig. 1 shows a vertical sectional view of the machine provided with the paste supplier.

Fig. 2 shows on enlarged scale the paste supplier in side elevation partly sectional.

Fig. 3 shows on enlarged scale the paste supplier in front elevation.

Fig. 4 shows on enlarged scale the paste supplier in plan view.

Fig. 5 shows diagrammatically in plan view the rolling table with a tobacco leaf applied thereto.

The frame 1 carries a rolling table 3 of known kind provided with an apron 2. The rear part of the apron is provided with a pocket 4, to which the filler is supplied in order to be moved later on by the roller 5 in the direction of the arrow.

A paste container 6 is carried by a yoke 7, connecting two rods 8, of which one is shown in Fig. 1. The rods are slidably guided by ears 9 in the frame, and one of them is provided with a collar 10 provided with shoulders and embraced by a fork on the end of an arm 11, forming part of a bell-crank lever, the second arm 12 of which is actuated by a cam disc 14 secured to a rotatable shaft 13, in such a way that vertical reciprocating movements are imparted to the rods 8 and consequently to the container 6 when the shaft rotates. The bell-crank lever is journaled on shaft 15 in the frame.

The container 6 comprises a front part 15 and a number of rear parts 16, vertically slidably and adjustable relative to the front part and nevertheless forming a tight paste reservoir. Each of said rear parts can be secured to the front part in any vertical position desired by means of screws 17 projecting through oblong holes 18 in said front part 15. Each rear part 16 at its bottom is provided with an outlet opening 19 for paste. Each opening is provided with a valve 20 actuated by a helical spring 21 for shutting the valve. The cone 22 of the valves is thus by the spring forced against the valve-seat 23 in the rear parts.

The front part 15 is rotatably journaled on a vertical shaft 24, to which it is to be secured in any desired angular position by a screw 25. The shaft 24 in its turn is slidably journaled in the hub 29 of an arm 26 and provided with a longitudinal groove 27, in which enters the end of a

pin 28 secured to the hub. The pin prevents the shaft 24 from rotating in the hub but not its longitudinal adjustment (changes in the height position). The shaft 24 protrudes above the hub 29 and to its top end is secured a ring 30 provided with a pin 31. The hub 29 is provided with a corresponding pin 32. The pins 31 and 32 are connected to each other by means of a tightened tension spring 33. The ring 30 has 10 an ear 34 provided with a stop screw 35, which by the spring 33 is forced against the arm 26. The arm 26 is slidably connected with an ear 36 of the yoke 7 and is to be secured to said ear in any desired position by means of a bolt 37, 15 extending through a longitudinal slot 38 in the ear and screwed in the arm.

In operating the apparatus the container 6 by the rods 8 is moved downwards against the rolling table 3, the bottom part 39 (shoulder) of 20 the valves 20, thus forming stops, hit the front edge of the tobacco leaf 40 applied to the apron 2. The valves yield against spring pressure and paste is delivered through the container openings 19.

25 If larger or smaller leaves are used, or if for some reason their front edge is adjusted forwards or backwards, the container can be adjusted in the corresponding direction by unscrewing the lock screw 31, which is fastened 30 again after adjustment of the container to the position desired. If the adjusting movement last mentioned is considerable, it may be desirable on account of the curved shape of the rolling table to also adjust the position of the container vertically. This is effected by means of actuating 35 the adjusting screw 35.

Fig. 5 shows a right hand leaf and a left hand leaf in full lines respectively dash and dotted lines. Their front edges 41 have different 40 oblique directions. When changing over from one kind of leaf to the other the screws 25 are unscrewed and the container is swung on the shaft 24 so that the valves, for instance from having had the position A as per Fig. 5 obtain 45 the position B. Thereby, however, the reciprocal levels of the surfaces, against which the stops 39 of the valves hit, are changed, and for this reason the vertical position of each rear part 16 is adjusted after unscrewing the screws 17, so that 50 when the container is moved downwards, all stops 39 hit the leaf simultaneously, and thus all valves yield simultaneously. This adjustment of the valves or of its stops should be made also in case the container 6 is moved by adjustment 55 in the direction forwards or backwards.

It is obvious that the device described above and illustrated in the drawings constitutes a special form of execution of the inventive idea underlying this application, and any other form 60 of execution might have been chosen for the purpose. The paste container may be stationary and in such case the stop (surface) which hit the stops of the valves is movable against the valve stops when the valves are to be opened. 65 The valves may be developed in any suitable manner (as needle-valves or conical valves), and as well their stops. The springs possibly may be eliminated if the weight of the valves is sufficient to press them down by gravity. Even 70 if the position of the stops according to the execution form described are adjusted by changing the position of the rear parts 16, this adjustment might be effected in another way, for instance by shortening or lengthening the valve extensions protruding through the opening 19. Ac-

cording to the preferred embodiment of the invention it was presumed that the apparatus should be operated in vertical direction. The operating direction is of no importance, however, for the scope of the invention. It may, for instance, be horizontal. With advantage the invention may be applied to a great number of other devices than to cigar machines, especially if sloping or curved pasting surfaces are to be supplied with paste, or if parts of the leaf separated from each other are to be pasted, in which case a suitable number of valves is released by sufficiently raising their stop.

What I claim as new and desire to secure by Letters Patent of the United States of America 15 is:—

1. In a device for paste supply, a paste container comprising a plurality of reciprocally adjustable valve casings each having a discharge opening, and a yielding valve in each opening. 20

2. In a device for paste supply, a paste container comprising a plurality of reciprocally adjustable elements constituting a wall of said container and each having a discharge opening, and a yielding valve in each opening. 25

3. In a device for paste supply, a paste container comprising a plurality of reciprocally adjustable valve casings each having a discharge opening, and a yielding valve in each opening, projecting out of the container. 30

4. In a device for paste supply, a paste container comprising a plurality of reciprocally adjustable elements constituting a wall of said container and each having a discharge opening, and a yielding valve in each opening, projecting out 35 of said container.

5. In a device for paste supply, a paste container comprising a plurality of reciprocally adjustable elements constituting a wall of said container and each having a discharge opening, and 40 a yielding valve in each opening, projecting out of the opening.

6. In a device for paste supply, a paste container having a rear wall, a plurality of reciprocally adjustable elements constituting said rear wall and each having a discharge opening, a yielding valve in each of said openings projecting out of the container, a shoulder, and means for engaging the valves with said shoulder to 45 open them. 50

7. In a device for paste supply, a paste container having a front wall and a rear wall, a plurality of reciprocally adjustable elements constituting said rear wall and each having a discharge opening, a yielding valve in each opening projecting out of the container, and means for securing said elements to the front wall of the container in a desired position. 55

8. In a device for paste supply, a paste container comprising a plurality of reciprocally adjustable elements constituting a wall of said container and each having a discharge opening, a yielding valve in each opening projecting out of the container, a stationary shoulder, and a mechanism for moving the container to engage 60 the valves with said shoulder to open them. 65

9. In a device for paste supply, a paste container having a plurality of discharge openings each provided with a yielding valve projecting out of the container, a curved, stationary shoulder, and a mechanism for moving the container to engage the valves with said shoulder to open them, said valves being reciprocally adjustable to engage said shoulder surface simultaneously. 70

10. In a device for paste supply, a paste con-

- tainer having a plurality of discharge openings provided with yielding, reciprocally adjustable valves projecting out of said container, a stationary shoulder, a mechanism for moving the container to engage the valves with said shoulder to open them, and means for adjusting the position of the container relative to the shoulder. 5
11. In a device for paste supply, a paste container having a plurality of discharge openings provided with yielding, reciprocally adjustable valves projecting out of said container, a stationary shoulder, and a mechanism for moving the container to engage the valves with said shoulder to open them, said container being adjustably and resiliently connected to said mechanism. 10
12. In a device for paste supply, a paste container having a plurality of discharge openings provided with yielding, reciprocally adjustable valves projecting out of said container, a curved shoulder, means for engaging the valves with said shoulder to open them, and means for adjusting the container to change the position of the container relative to said shoulder. 15
13. In a device for paste supply, a rotary paste container having a plurality of discharge openings provided with yielding, reciprocally adjustable valves projecting out of said container, a shoulder, means for engaging the valves with said shoulder to open them, and means for adjusting the container to change the angular position of the container relative to said shoulder. 20
14. In a device for paste supply, a rotary paste container having a plurality of discharge openings provided with yielding, reciprocally adjustable valves projecting out of said container, a curved shoulder, means for engaging the valves with said shoulder to open them, and means for adjusting the container to change the angular position of the container relative to said shoulder. 25
15. In a device for paste supply, a paste container having a plurality of discharge openings provided with yielding, reciprocally adjustable valves projecting out of said container, a shoulder, means for engaging the valves with said shoulder to open them, and means for adjusting the container to change the distance between the container and said shoulder. 30
16. In a device for paste supply, a stationary shoulder, a paste container having a plurality of discharge openings provided with yielding, reciprocally adjustable valves projecting out of said container, a continuously reciprocated rod, an arm mounted on said rod, a carrier rod slidably and adjustably guided in said arm and carrying the container, and means for continuously operating the reciprocated rod to periodically engage the valves with the shoulder to open them. 35
17. In a device for paste supply, a stationary shoulder, a paste container having a plurality of discharge openings provided with yielding, reciprocally adjustable valves projecting out of said container, a continuously reciprocated rod, an arm mounted on said rod, a carrier rod slidably and adjustably guided in said arm and carrying the container, means for continuously operating the reciprocated rod to periodically engage the valves with the shoulder and open them, and means for adjusting the container to change the angular position of said container on the carrier rod. 40
18. In a device for paste supply for cigar machines, the combination with a curved rolling table, of a rolling apron lying upon said table, a paste container above said table having a plurality of discharge openings in its bottom end provided with yielding, reciprocally adjustable valves projecting out of the openings, and means for moving the container to engage the valves with said apron to open them. 45
19. In a device for paste supply for cigar machines, the combination with a curved rolling table, of a rolling apron lying upon said table, a rotary paste container above said table having a plurality of discharge openings in its bottom end provided with yielding, reciprocally adjustable valves projecting out of the openings, and means for moving the container to engage the valves with said apron to open them, said container being angularly adjustable relative to said table. 50
20. In a device for paste supply for cigar machines, the combination with a curved rolling table, of a rolling apron lying upon said table, a paste container above said table having a plurality of discharge openings in its bottom end provided with yielding, reciprocally adjustable valves projecting out of the openings, means for moving the container to engage the valves with said apron to open them, and means for adjusting the container to change the distance between the container and the apron. 55
21. In a device for paste supply for cigar machines, the combination with a curved rolling table, of a rolling apron lying upon said table, a paste container above said table having a plurality of vertically reciprocably adjustable casings each having a discharge opening in its bottom end, a yielding valve in each opening projecting out of said openings, and means for moving the container to engage the valves with said apron to open them. 60
22. In a device for paste supply for cigar machines, the combination with a curved rolling table, of a rolling apron lying upon said table, a paste container above said table having a plurality of vertically reciprocably adjustable elements constituting a wall of said container and each having a discharge opening in its bottom end, a yielding valve in each opening projecting out of said openings, and means for moving the container to engage the valves with said apron to open them. 65
23. In a device for paste supply, a paste container having a plurality of discharge openings, a yielding valve in each opening having a shoulder, and means for adjusting said shoulders to occupy desired reciprocal positions when the valves are closed. 70
24. In a device for paste supply, a paste container having a plurality of discharge openings, a yielding valve in each opening having an extension projecting out of said container, and means for adjusting said extensions to occupy desired reciprocal positions when the valves are closed. 75
25. In a device for paste supply, a paste container having a plurality of discharge openings, a spring actuated valve in each opening having an extension projecting out of said container, and means for adjusting said extensions to occupy desired reciprocal positions when the valves are closed. 80
26. In a device for paste supply, a paste container having a plurality of discharge openings, a yielding valve in each opening having an extension projecting out of said container, means for adjusting said extensions to occupy desired reciprocal positions when the valves are closed, and a shoulder for engaging said extensions to open said valves. 85

27. In a device for paste supply, a paste container having a plurality of discharge openings, a yielding valve in each opening having an extension projecting out of said container, means for adjusting said extensions to occupy desired reciprocal positions when the valves are closed, 5 and a curved shoulder for engaging said extensions to open them.
28. In a device for paste supply, a paste container having a plurality of discharge openings, 10 a yielding valve in each opening having an extension projecting out of said container, means

for adjusting said extensions to occupy desired reciprocal positions when the valves are closed, a stationary shoulder, and means for moving the container to engage said extensions with said shoulder to open said valves. 5

29. In a device for paste supply, a paste container comprising a plurality of reciprocally adjustable valve casings each having a discharge opening, and a yielding valve in each opening, projecting out of the opening. 10
